United States Patent Office

Des. 214,911
Patented Aug. 12, 1969

214,911

LIGHTING DEVICE

Robert G. Morgan, Ipswich, Mass., assignor to Sylvania
Electric Products Inc., a corporation of Delaware

Filed June 1, 1967, Ser. No. 7,322

Term of patent 14 years

Int. Cl. D26—01

U.S. Cl. D26—8

FIG.1

FIG.2

FIG.3

FIG.4

FIGURE 1 is a perspective view of a lighting device showing my new design.

FIGURE 2 is a bottom view thereof.

FIGURE 3 is a top view thereof with one form of indicia which may be used therewith being shown in phantom.

FIGURE 4 is a side elevational view thereof.

The dominant features of my design reside in the portions shown in full lines.

I claim:

The ornamental design for a lighting device, as shown and described.
